UNITED STATES PATENT OFFICE.

JOHN BACON HOLTON, OF WASHINGTON, KENTUCKY.

GATE.

SPECIFICATION forming part of Letters Patent No. 373,978, dated November 29, 1887.

Application filed July 18, 1887. Serial No. 244,643. (No model.)

To all whom it may concern:

Be it known that I, JOHN BACON HOLTON, of Washington, in the county of Mason and State of Kentucky, have invented a new and 5 Improved Gate, of which the following is a full, clear, and exact description.

My invention relates to gates used with fences for lands, and has for its object to provide an inexpensive gate of this character 10 which has durability and will work easily by reason of the facilities afforded by its construction to prevent or correct tendency of the gate to sag, and to support it when closed, so as to relieve its frame, hinges, and latch, and also 15 the gate-post, of racking strains.

The invention consists in certain novel features of construction and combinations of parts of the gate, all as hereinafter described and claimed.

20 Reference is to be had to the accompanying drawings, forming a part of this specification, in which similar letters of reference indicate corresponding parts in all the figures.

Figure 1 is a side view of my improved gate. 25 Fig. 2 is a side view of part of a gate, showing a modified construction; and Fig. 3 is a transverse vertical sectional elevation taken on the line 1 1; Fig. 1.

The frame of the gate consists, mainly, of two 30 uprights, A B, at its hinge and latch ends, respectively, upper and lower bars or rails, C D, framed or otherwise suitably connected to the uprights, a diagonal brace, E, which is secured at opposite ends by bolts e e' to the upright A. 35 and rail C, and is haled into the lower rail, D, and a base board, F, which is fixed to the parts A B D at or near the bottom of the gate. The tops of the uprights A B, which project above the top rail, C, are connected by a truss- 40 rod, G, which passes through a hole or slot in the top of an angular metal plate, H, which is held to the gate-rail C partly by the same bolt, e', which holds the brace E to this rail.

Between the uprights A B are stretched a 45 series of longitudinally-ranging stay rods or wires, I, which have heads at one end and bolt ends and nuts at the other end, and these rods pass through the diagonal brace E, and also through a vertically-ranging metal stay bar or 50 plate, J, the lower part of which is twisted one-quarter around from the plane of the body of the bar through which the rods I pass and enters a slot in the lower rail, D, whereto it is

held by a bolt or pin, j'. The upper end of the bar J is rounded and screw-threaded to 55 form a bolt end, j, and on it is fitted a tapped screw-plate, K, which bears against the under side of the top rail, C, of the gate. The bolt end j passes through the rail C, and also through the outer end portion of the angle-plate H, and 60 above this plate receives a nut, k, which, when tightened and in connection with the bolt e', above named, holds the plate H firmly to the top of the gate.

It is obvious that with the gate proper constructed as above described there is very little liability of a disjointing of the gate, either laterally or vertically, and the tendency of the gate to sag is reduced to a minimum.

The gate is hung to the hinge-post L by 70 means of two bolts, M, having eyes m, which encircle the post, and have nuts m', which are fitted to the threaded stems of the bolts and are clamped to opposite edges of the hinge-upright A of the gate, with or without interposed washers. The stem of the upper eye-bolt, M, is prolonged to form a brace-rod, N, which passes forward through the diagonal brace E, and has a threaded extremity, onto which and outside of the brace is screwed a 80 nut, n, which takes against a shoulder, n', provided for it on the brace.

It is obvious that the slight tendency the gate has to sag may be corrected by screwing up the nut n of the stay-bar in connection 85 with adjustment of the nuts m' m' on the eye-bolts M.

Each of the gate-uprights A B is provided at its lower end with a roller, which is preferably fitted in a slot in the upright and held 90 in said slot by its pin or axle, which passes through the upright. The roller O on the upright A is adapted to rest and travel on a metal plate, P, which may be a part of the post L, but which is shown fixed to the foundation or sill plate or post R, onto or into which the hinge-post L is fitted. This plate P is con-eaved to provide two opposite inclined faces, p p, on one or the other of which the roller O travels as the gate opens in one direction or 100 the other, whereby the gate will be lifted bodily, and when fully open will have support by the roller O on the flat upper faces of the plate, and when the gate is pushed partly closed from its fully-opened position it will be 105 caused to close automatically by its own grav-

ity as the roller O rides down one of the inclined faces p of the plate P. The other roller, O', on the upright B is adapted to ride upon a metal plate, P', which is fixed to the sill plate 5 or post R', onto or into which is fitted the latch-post S of the gate. The opposite ends of the plate P' are inclined or beveled, to allow the roller O' to ride easily onto the plate as the gate closes from either side.

10 It is obvious that the entire weight of the gate will be supported by the rollers on the plates P P', whereby sagging or vertical rocking of the gate is almost wholly prevented when the gate is closed, and the gate-hinges 15 are entirely relieved of racking strains, and the posts are also relieved of all strain but the vertical pressure of the gate upon the sills R R', and the gate-latch is also free from pressure or strain.

20 The gate-latch comprises a couple of bolts, T T, which are fitted to slide horizontally in the gate-upright B, and preferably within metal cups or bushings t t, fitted in the upright. The bolts T are each provided with a collar or shoulder, u, between which and the inner end of the adjacent bushing t an expanding sprung, U, is placed, so as normally 25 to force the bolt outward into engagement with an opening in a double-inclined catch-plate, s, which is fixed by bolts or screws to the latch-post. The inner ends of the bolts T are formed, preferably, as eyes for convenient connection of them by links or chains V, with cranks w, which are formed as bends of 30 a latch-operating bar, W, which is journaled in the gate-rails C D, and at its top carries a crank-arm, w', by partially turning which in either direction both bolts T will be simultaneously withdrawn from their catch-plates 35 s to allow the gate to be swung open. When the crank w' is let go, the latch-bolt springs restore the bolts T and the bar W to normal positions. (Shown in Fig. 1 of the drawings.)

40 The gate proper (shown in part in Fig. 2 of the drawings) is made like the gate above described, but has a modified form of its hinging devices, as follows: A hinge-bar, X, is bent outward at a right angle at its upper part, 45 and said part, which passes through the gate-upright A, is screw-threaded to receive nuts x' x' at opposite faces of the upright, and the vertical portion of the bar X passes through the eyes of screw-bolts l l, fastened in 50 the hinge-post L', and below the lower eyebolt l the bar passes freely through the eye of a bolt, M', which is passed through the gate-upright A and receives nuts m' m' at opposite faces of the upright. The upper part of the 55 hinge-bar X is prolonged forward to form a brace, N', which, like the rod N, above described, passes through the diagonal brace E of the gate and receives a nut, n, by tightening which, in connection with the adjustment 60 of the nuts x' x' m' m', any tendency of the gate to sag may be corrected.

It is obvious that both the brace-rods N N' have the same peculiarity of construction in connection with the gate-hinge—that is to say, the brace-rod in each instance is formed as a 70 prolongation of one of the members of a hinge of the gate, which promotes economical construction and durability of the gate.

The weight of the gate is sustained by the bearing of the upper part, x, of the bar X on 75 the upper eyebolt l, as shown in Fig. 2 of the drawings.

Having thus described my invention, what I claim as new, and desire to secure by Letters Patent, is—

1. The combination, with the uprights A B and longitudinal rails C D, of the angle-plate bolted upon the top rail, C, the truss-rod extending through the upper ends of the uprights and angle-plate, the vertical stay-bar J, twisted at its lower end at right angles to its main part, provided with a series of apertures, screw-threaded at its upper end, and passed through the top rail, the plate K, nut k, the bolt or pin j', securing the lower 90 end of the bar J to the lower rail, and the longitudinal wires passing through said bar and secured to the uprights, substantially as set forth.

2. The combination, in a gate, of uprights A B, top and bottom rails, C D, and a diagonal brace, E, connecting the parts A C, an angle-plate, H, fixed at the top of rail C by a bolt, e', which holds the upper end of the brace E, and by a bolt end, j, of a vertical stay-bar held to the bottom rail of the gate, a screw-plate, K, on the bar J below the rail C, and a nut, k, on the bar above said rail, and a truss rod, G, connected to opposite upper ends of the gate-uprights A B and bearing on the vertical part of the angle-plate H, substantially as described, for the purposes set forth.

3. In a gate constructed with end uprights and longitudinal rails A B C D, a diagonal 110 brace, E, and longitudinal stay rods or wires I, arranged substantially as specified, the combination, with the rails C D and rods I, of a vertical stay-bar, J, through which the rods I pass, and which is connected to the rail D and 115 to the rail C by a screw-plate, K, and nut k on the upper threaded end of the bar, substantially as shown and described.

4. In a hinged gate, the combination, with the gate-frame, of spring-pressed latch-bolts T 120 thereon, a vertically-ranging rod, W, journaled in the frame and provided with cranks w and a crank-arm, w', and links V, connecting the bolts T and cranks w, and adapted, when the rod W is turned, to withdraw the bolts from 125 a catch-plate or recess in a latch-post, substantially as herein set forth.

JOHN BACON HOLTON.
